LOCOMOTIVE BOILER

John J. Daly, Virginville, Pa.

Application October 23, 1933, Serial No. 694,842

4 Claims. (Cl. 122—68)

This invention is a tubular boiler structure of the type adapted for railroad locomotives.

One of the objects of the invention is to provide an improved boiler of the character mentioned, so constructed and arranged that the necessity of employing fire brick in the construction of the fire-box arch is avoided, thereby greatly reducing the cost of boiler maintenance. A further object is to provide a strong but flexible boiler construction, in which the safety factor is materially increased by improved water circulation. A further object is to provide an increased water heating surface, and means whereby all of the parts are readily accessible for inspection and repair. A further object is to provide a supplemental water chamber, so positioned as to intercept and deflect the products of combustion in the fire box, in such manner as to effectively heat said chamber on two sides, said arch being positioned at any desired angle, and constructed of any selected width longitudinally of the fire box. A further object is to provide means by which a crown sheet is firmly and safely supported by said supplemental chamber, and the water circulation greatly improved.

The invention will be hereinafter fully set forth and particularly pointed out in the claims.

In the accompanying drawings:—

Fig. 1 is a longitudinal sectional view illustrating a portion of the fire box of a standard type locomotive boiler,

Fig. 2 is a transverse sectional view on the line 2—2 of Fig. 1,

Fig. 3 is a top view of the supplemental water chamber, and

Fig. 4 is a top plan view of the crown sheet.

Referring to the drawings, 10 designates an inner shell, of the type which normally encloses the fire box F of a locomotive, and 11 is the outer shell, said shells being supported in relatively spaced relation in the usual manner by means of staybolts 12, so as to provide a water space W between the shells and a throat T, as clearly shown in the drawings. The crown sheet 13 of the inner shell is provided with a plurality of relatively spaced elongated openings 14, and the side walls of said sheet are also provided with rearwardly and upwardly inclined elongated openings 15, leading rearwardly and upwardly from the throat T.

Extending transversely of the fire box F is a supplemental water chamber X, which includes a bottom wall 16 extending the full width of the fire box and having an upturned flange 17 at its upper end and a downturned flange 18 at its lower

edge. The end edges of the bottom wall 16, and the flange 17 fit within the openings 15 in the sides of the inner shell. The lower end flange fits within and is secured to a complementary edge of an elongated opening 15a in the inner shell 10 at the throat T.

The top of the chamber X consists of an archsheet 25 having flanges 24 which also fit within the elongated opening 15 in the sides of the inner shell. The lower edge of said flange also fits within the opening 15a and is secured to an edge of said opening. Said sheet 25 is also provided with a plurality of elongated openings 23 parallel to and in register with the openings 14 of the crown sheet.

Depending from the crown sheet 13 are a plurality of narrow water legs L, each of which has flanges 19 at its upper portion, extending into and secured within the openings 14 in the crown sheet. The front wall 20 of each leg L is longer than the rear wall 21, and each leg is provided at its lower end with a flange 22, which is secured to the free edge of an opening 23 in the arch sheet 25. It will be noted that three legs L are shown with the middle leg somewhat longer than the others. However, the flanges 17 and 24 abut at the upper edge of chamber X as indicated at 32, see Fig. 1. Wherever the flanges 17, 24, 18, 19 and 22 abut against other metal parts they are preferably united to the contiguous parts by welding, in a well known manner. The top wall or arch sheet 25 is connected with bottom wall 16 by tubes A to permit passage of products of combustion to pass through the reduced portion R of the chamber.

It will thus be seen that the chamber X consists of a bottom wall extending the full width of the fire box, a top wall consisting of the arch sheet 25, and the supporting legs L, communication between the chamber X and the water space being established at the top, the sides and the throat of the boiler. In order to supplement the welded joints, the flanges 17 and 24 top and bottom walls, respectively, of the chamber X are secured to the side walls of the inner shell 10 by means of the stay bolts 12, as shown. In a similar manner, the lower wall 16 is secured to the arch sheet 25 by means of stay bolts 33 as shown. The flanges 19 are also secured to the crown of the outer shell 11 by means of the stay bolts 12, as clearly shown in the drawings, and the flanges 22 are secured to the bottom wall 16 by the stay bolts 33. The lower portion R is also braced by the tubes A.

In order to provide for ready access to the interior of the boiler for inspection and cleaning,

the outer shell is provided with a plurality of openings 35, in positions registering with the legs L closed by removable plugs 36, and similar openings 35 are provided in the side walls of said outer shell in line with the ends of chamber X, said openings also being closed by similar plugs 36. It will also be noted that the throat T is provided with similarly plug-closed openings 37, opposite to the reduced portion R.

10 In operation, the products of combustion from the fire box will be driven forwardly by the draft, until they impinge against the bottom wall 16 of the chamber X. They will then be deflected rearwardly and upwardly until they can pass over 15 and through the fire box in contact with the upper walls 25 and side walls of the legs L. Some of the products of combustion will also pass directly through the flues A. In this manner the chamber X serves somewhat the functions of a super- 20 heater, and the water is caused to take up a very definite course of circulation. That is to say, the colder water enters the chamber X from the throat T through reduced portion R, and flows upwardly as it becomes heated. From the chamber 25 the heated water is delivered by the legs L to the space W, above the inner shell, thereby making the circulation from the throat T to the top or steam space of the boiler, and then back 30 between the shells to the throat again.

30 The advantages of the invention will be readily understood by those skilled in the art to which it appertains. It will be noted, for instance, that by employing the chamber X in the manner described and using it as a water heater, so that 35 it is normally filled with water, there is no necessity for utilizing fire brick to protect it from the heat. Therefore, by means of the invention, there is a great saving in the expense due to the elimination of the fire brick and a considerable 40 reduction in the cost of maintenance. A further advantage is that the chamber X, and the crown of the inner shell are so connected that said chamber tends to brace said crown, and yet 45 there is the required flexibility necessary for safe operation. At the same time the safety factor is greatly increased by improving the water circulation and preventing the burning out of the parts. Another important advantage is that 50 there is a substantial increase of the water heating surface and all of the parts are readily accessible for inspection and repair.

Having thus described my invention, I claim:—

1. A boiler of the character described comprising an inner fire-box-enclosing shell, an outer shell, said shells being so constructed and arranged as to provide an intervening water space and a water throat between them, said inner shell having relatively spaced elongated openings in the crown portion thereof, an opening in the throat and an elongated opening in each of the side walls thereof, the last mentioned openings leading upwardly and rearwardly from said throat, an inclined shallow chamber having open 55 ends secured within said side openings and an open lower side portion in communication with said throat opening, fire tubes in said lower side portion, and legs secured within the openings in the crown of said inner shell and also secured to said chamber in a manner to communicate with the interior thereof, said legs being relatively spaced and each extending approximately the full length of said chamber.

2. A boiler of the character described comprising an inner fire-box-enclosing shell, an outer

shell, said shells being so constructed and arranged as to provide an intervening water space and a lower water throat between them, said inner shell having relatively elongated openings in the crown portion thereof and also having an elongated upwardly and rearwardly inclined opening in each of the sides thereof leading from said throat, an inclined shallow chamber having open ends secured within said side openings and an open lower side in communication with said throat, fire tubes passing through said lower side, the top wall of said chamber also having elongated openings therein in register with the respective openings in the crown portion of said inner shell and extending approximately the full width of the chamber, and legs having their upper portions secured within the openings of said crown portion and having their lower portions secured in the openings of said chamber forwardly of said throat.

3. A boiler of the character described comprising an inner fire-box-enclosing shell, an outer shell, said shells being so constructed and arranged as to provide an intervening water space and a water throat between them, said inner shell having relatively spaced elongated openings in the crown portion thereof, an opening in the throat and an elongated opening in each of the side walls thereof, the last mentioned openings leading upwardly and rearwardly from said throat, a shallow chamber consisting of a bottom wall and a top wall, said chamber having open ends secured within said side openings and an open lower side portion in communication with said throat, fire tubes passing through said lower side portion, said top wall having elongated openings opposite to the respective openings in said inner shell and relatively spaced hollow water legs having their upper portions secured within the openings in the crown of the inner shell so as to communicate with said water space and having their lower portions secured within the openings of said top wall so as to communicate with the chamber, said legs having their forward ends disposed rearwardly of said throat.

4. A boiler of the character described comprising an inner fire-box-enclosing shell, an outer shell, said shells being so constructed and arranged as to provide an intervening water space and a water throat between them, said inner shell having relatively spaced elongated openings in the crown portion thereof, an elongated opening in the throat and an elongated opening in each of the side walls thereof, the last mentioned openings leading upwardly and rearwardly from said throat opening and terminating a substantial distance below said crown portion, an inclined shallow chamber consisting of flanged open ends engaging and secured to the edges of said side openings, and an open lower side portion provided with flanges engaging and secured to the edges of the opening in said throat, said chamber having elongated openings in its top wall, the forward ends of said openings terminating rearwardly of the forward end of said chamber, water legs having flanges at their upper ends engaging and secured to the openings in said crown portion, and having flanges at their lower ends engaging and secured to the edges of said top wall openings, and fire tubes passing through said chamber between the boiler throat and the forward ends of said legs.

JOHN J. DALY. 75
